(57) **CLAIM**

The ornamental design for a snap on accessory bracket, as shown and described.

DESCRIPTION

FIG. 1 is a perspective view of a snap on accessory bracket showing my new design;

FIG. 2 is a front view thereof;

FIG. 3 is a rear view thereof;

FIG. 4 is a right side thereof;

FIG. 5 is a left side thereof;

FIG. 6 is a top view thereof;

FIG. 7 is a bottom view thereof; and,

FIG. 8 is a perspective view thereof shown in an environment of use.

The broken lines in FIG. 8 showing part of a cable tray system illustrates environmental subject matter only and forms no part of the claimed design.

1 Claim, 6 Drawing Sheets

FIG. 1

FIG. 2

FIG. 3

FIG. 4

FIG. 5

FIG. 6

FIG. 7

FIG. 8
